UNITED STATES PATENT OFFICE.

GEORGE ALAN MORE, OF NORTH SYDNEY, NEW SOUTH WALES, AUSTRALIA.

BOILER-INDICATOR.

1,199,096.

Specification of Letters Patent. Patented Sept. 26, 1916.

Application filed May 27, 1914. Serial No. 841,209.

To all whom it may concern:

Be it known that I, GEORGE ALAN MORE, a subject of Great Britain, residing at "Altona," Berry street, North Sydney, in the 5 State of New South Wales, Commonwealth of Australia, have invented new and useful Improvements in Boiler-Indicators, of which the following is a specification.

This invention relates to that class of apparatus employed for recording variations of level of water in steam boilers in which mechanism actuated by the changes of water levels in the boiler, records such variations automatically and continuously.

15 Heretofore the mechanical connection between the inclosed or water operated portion of the mechanism and the exteriorly placed mechanism has consisted of a spindle passing through a stuffing box and packing. 20 This arrangement is objectionable in so far that friction of a varying amount is periodically encountered by virtue of the wearing of the packing and more especially when the gland is tightened up to obviate leakage. 25 This periodical varying of the friction between the packing and the spindle militates against accurate records of varying water levels being obtained and may also lead, by excessive friction, to the sticking and thereby 30 by possible breaking by torsion of the packed spindle.

This invention consists in the employment of a spindle whereby the stuffing box with its packing is dispensed with, and whereby friction is reduced to a small but constant quantity.

Referring to the annexed sheets of explanatory drawings Figure 1 is a perspective view of the apparatus. Fig. 2 is a vertical section thereof. Fig. 3 is a horizontal section taken on line 3—3 Fig. 2. Fig. 4 is a vertical section taken on line 4—4 Fig. 2. Fig. 5 is a horizontal section taken on line 5—5 Fig. 4. Fig. 6 is a sectional perspective view of the cam supporting shaft with its extension, and Fig. 7 is a view of the graduated card chart upon which the record of water levels is automatically recorded.

Corresponding numerals indicate corresponding parts in the drawings.

10 is the water chamber to which water from the steam boiler whose water levels are to be indicated is admitted through the orifice 11.

12 is a float which is actuated by the rising

and falling of the contained water in chamber 10.

13 is a steam orifice from which a connection is made between the apparatus and steam space of the boiler.

60 The float rod 14 is pivotally connected to the free end of the lever 15 which latter is fulcrumed at 16.

The boss 17 of the lever 15 is constructed as shown in section in Figs. 2 and 4 in the 65 form of a double cam the upper portion of which is of less diameter than the lower.

The lever axis or fulcrum 16 is trunnioned at one end (Fig. 4) in a screwed steam tight plug 18 and at the other end a portion 19 is 70 trunnioned in a hollow plug 20. The outer end 21 of the fulcrum is formed as a square and engages in horizontal sliding contact with a rectangularly formed chamber constructed in the boss 22 of the steam valve 75 23. A spiral spring 24 within the rectangular chamber forces the valve 23 up to its face and obviates leakage of steam from the interior of the apparatus to the atmosphere. An extension spindle 25 is formed, in one, 80 with the head of the valve 23, and is suitably journaled in the mounting 26 to permit the valve 23 sufficient freedom to settle itself accurately in its seating. To the outer end of this spindle is secured a lever 27 at the 85 free end of which is pivotally attached a connecting rod 28 carrying at its outer end a recording pen or pencil 29 suitably held in rubbing contact with a rotating card or chart 30 upon which when in operation a 90 line 31 is traced by such pen or pencil 29. Clockwork mechanism 32 rotates this card or chart 30 at a predetermined speed and the various markings and indexes thereon determine the precise time at which variations from the datum circle 33 took place and the extent of such variations.

95 In lieu of the valve 23 a stuffing box or gland may be used; in which case one end of the fulcrum 16 is extended outwardly to 100 carry the lever 27 and passes through the said stuffing box or gland.

The mechanism for operating the steam whistle alarm shown in Figs. 2 and 4 comprises the spindle 34 which is forked at its 105 lower end forming curved or bowed tines or prongs 35 which straddle the upper or smaller portion of the boss 17 of the lever 15. The upper portion of the vertical spindle 34 is pivotally attached to the spider frame 110

- support 36. This frame 36 slides within the casing 37 which is made adjustable in vertical plane by means of the screwed thread by which it is secured to its seating. This vertical adjustment of the casing 37 permits of the range of high and low water marks being increased or decreased within certain limits before the alarm whistle is sounded to announce either high or low water level.
- 5 10 Thus by the raising of the casing 37 by partially unscrewing it in its seating the range between high and low water marks is increased and alternately by screwing it downward the range is decreased automatically.
- 15 In Fig. 4 the casing 37 is shown in its lowest vertical position. The crosshead 38 of this support carries a conically shaped steam valve 39 which takes its seating on the removable steam passage 40. 41 is a screwed gland which secures the lower flange of the steam pipe 42 in place. Upon the lifting of the valve 39 from its seating 40 live steam is permitted to flow from the interior of the apparatus through the pipe 42 to sound an
- 20 25 alarm whistle.

Test of the efficient working of the apparatus is carried out by alternately closing the water and steam services while keeping the drain cock 46 open during such proceedings. By this means any stoppage or partial stoppage of flow in either the steam or water supply pipes is discovered. 45 is a water gage glass adapted to visually indicate the height of water in the water chamber 10 of the apparatus.

In operation water and steam from the boiler to which the apparatus is attached are turned on; water from the boiler coming through the orifice 11 into the water chamber 10 and steam through the orifice 13 into the steam chamber. The water in the chamber 10 and steam in the steam space are under the same or approximately the same pressure as that existing in the boiler, consequently the water level in the chamber 10 moves in unison with the water level in the boiler. Upon the water level in the boiler being either raised or lowered the float 12 is automatically raised or lowered by the water level of the contained water within the chamber 10 moving in unison with the boiler water level. This action causes the free end 43 of the lever 15 to be raised or lowered accordingly by the action of the float rod 12.

55 The opening of the steam whistle valve 39 is effected by means of the shoulders 44 of the cam 17 coming into contact with either one or other of the tines or prongs 35 of the spindle 34 when the lever 15 is raised or depressed. The valve 39 is closed when the lever 15 is in normal position. The opening of the valve 39 permits a stream of live steam to flow from the steam space of the apparatus to sound an alarm to indicate 60 65 a predetermined high and low water level.

The movement of the float actuated lever 15 in partially rotating its axis causes the extension spindle 25 to move the lever 27 through an arc of a circle thus advancing and retiring the connecting rod 28 with its 70 attached pen or pencil 29.

The advancing and retiring movements of the pen or pencil causes the indication by means of a more or less distorted circular figure drawn by the pen or pencil about the 75 datum circle to graphically record the extent of the range of varying water levels in the boiler. As the card chart is clockwork or otherwise driven at a predetermined speed the marking thereon graphically gives the 80 particulars of time at which these variations took place.

What I claim as my invention and desire to secure by Letters Patent is.—

1. In an apparatus of the class described, 85 the combination of a steam-tight casing affording a water column for a boiler, the casing being provided with a bearing opening presenting a valve seat at its inner end, a spindle mounted within the casing and including two members mounted to rotate in unison and having axially sliding contact with each other, one member being incapable of axial movement within its bearings and the other being capable of such movement 90 and extended through the said bearing opening in the casing; a spherically shaped valve plug of rigid material provided upon the latter member for frictional contact with the seat at the inner end of said opening, the said plug having independent radial movement, through its member being in loose axial contact with the axially immovable member, to provide a normal seating to afford uniform friction and a steam tight joint at the bearing opening; indicating means disposed exteriorly of the casing and associated operatively with the protruding spindle member; and water level actuated means provided within the casing for operating the other spindle member.

2. In an apparatus of the class described, 115 the combination of a steam-tight casing affording a water column for a boiler, the casing being provided with a bearing opening presenting a valve seat at its inner end, a spindle mounted within the casing and including two members mounted to rotate in unison and having axially sliding contact with each other, one member being incapable of axial movement within its bearings and the other being capable of such movement and extended through the said bearing opening in the casing; a spherically shaped valve 120 plug of rigid material provided upon the latter member for frictional contact with the seat at the inner end of said opening, the said plug having independent radial movement, through its member being in loose axial contact with the axially immovable 125 130

member to provide a normal seating to afford uniform friction and a steam tight joint at the bearing opening; indicating means disposed exteriorly of the casing and associated operatively with the protruding spindle member, water level actuated means provided within the casing for operating the other spindle member, and resilient means for pressing the valve plug against its seat 10 until the steam is admitted to the casing from the boiler.

3. In an apparatus of the class described, the combination of a steam-tight casing affording a water column for a boiler, the casing being provided with a bearing opening presenting a valve seat at its inner end, a spindle mounted within the casing and including two members mounted to rotate in unison and having axially sliding contact 15 with each other, one member being incapable of axial movement within its bearings and the other being capable of such movement and extended through the said bearing opening in the casing, a spherically shaped valve 20 plug of rigid material provided upon the latter member for frictional contact with the seat at the inner end of said opening, the said plug having independent radial movement, through its member being in loose 25 axial contact with the axially immovable member, to provide a normal seating to afford uniform friction and a steam-tight joint at the bearing opening; indicating means disposed exteriorly of the casing and 30 associated operatively with the protruding spindle member; water level actuated means provided within the casing for operating the other spindle member, and a compression spring associated with the spindle and tending 35 to separate the members of the same to press the valve against its seat, until the steam is admitted to the casing from the 40 boiler.

4. In an apparatus of the class described, the combination of a steam-tight casing affording a water column for a boiler, the casing being provided with a bearing opening presenting a valve seat at its inner end, a spindle mounted within the casing and including two members mounted to rotate in unison and having axially sliding contact 45 with each other, one member being incapable of axial movement within its bearings and the other being capable of such movement and extended through the said bearing opening in the casing; a spherically shaped valve 50 plug of rigid material provided upon the latter member for frictional contact with the seat at the inner end of said opening, the said plug having independent radial movement, through its member being in loose 55 axial contact with the axially immovable member, to provide a normal seating to afford uniform friction and a steam-tight joint at the bearing opening; indicating 60

means disposed exteriorly of the casing and associated operatively with the protruding spindle member, and water level actuated means provided within the casing for operating the other spindle member, one of said 70 spindle members being provided in its inner end with a non-circular recess and the other member being provided with a reduced non-circular extension upon its inner end for axial sliding engagement within the 75 recess of the first member.

5. In an apparatus of the class described, the combination of a steam-tight casing affording a water column for a boiler, the casing being provided with a bearing opening 80 presenting a valve seat at its inner end, a spindle mounted within the casing and including two members mounted to rotate in unison and having axially sliding contact with each other, one member being incapable 85 of axial movement and the other being capable of such movement and extended through the said bearing opening in the casing; a spherically shaped valve plug of rigid material provided upon the latter member for 90 frictional contact with the seat at the inner end of said opening, the said plug having independent radial movement through its member being in loose axial contact with the axially immovable member, to provide a 95 normal seating to afford uniform friction and a steam-tight joint at the bearing opening; indicating means disposed exteriorly of the casing and associated operatively with the protruding spindle member; water level 100 actuated means provided within the casing for operating the other spindle member, one of said spindle members being provided in its inner end with a non-circular recess and the other member being provided with a reduced 105 non-circular extension upon its inner end for axial sliding engagement within the recess of the first member, and resilient means tending to separate the said spindle members to maintain the said valve plug 110 seated until the steam is admitted to the casing from the boiler.

6. In an apparatus of the class described, the combination of a steam-tight casing affording a water column for a boiler, the casing being provided with a bearing opening presenting a valve seat at its inner end, a spindle mounted within the casing and including two members mounted to rotate in unison and having axially sliding contact 115 with each other, one member being incapable of axial movement within its bearings and the other being capable of such movement and extended through the said bearing opening in the casing; a spherically shaped valve plug of rigid material 120 provided upon the latter member for frictional contact with the seat at the inner end of said opening, the said plug having independent radial movement through its mem- 125

ber being in loose axial contact with the axially immovable member, to provide a normal seating to afford uniform friction and a steam-tight joint at the bearing opening; indicating means disposed exteriorly of the casing and associated operatively with the protruding spindle member; water level actuated means provided within the casing for operating the other spindle member, one of said spindle members being provided in its inner end with a non-circular recess and the other member being provided with a reduced non-circular extension upon its inner end for axial sliding engagement with-

in the recess of the first member, and a compression spring mounted within the said recess in interposed relation to both spindle members and tending normally to separate the members of the same until the steam is admitted to the casing from the boiler.

In testimony whereof I have signed my name to this specification in the presence of two subscribing witnesses.

GEORGE ALAN MORE.
